UNITED STATES PATENT OFFICE.

MORIL V. ANDREWS AND STEPHEN W. HOLMAN, OF MINNEAPOLIS, MINNESOTA.

COMPOUND ROTARY MOTOR-PUMP.

1,332,153.

Specification of Letters Patent. Patented Feb. 24, 1920.

Application filed December 31, 1919. Serial No. 348,527.

To all whom it may concern:

Be it known that we, MORIL V. ANDREWS and STEPHEN W. HOLMAN, citizens of the United States, residing at Minneapolis, in the county of Hennepin and State of Minnesota, have invented certain new and useful Improvements in Compound Rotary Motor-Pumps, of which the following is a specification.

10 This invention relates to rotary vacuum pumps and pertains especially to compound rotary pumps.

This invention comprises important improvements in and variations of the pump 15 patent allowed October 20th, 1919, Serial No. 326,187, on our application filed in the United States Patent Office September 25th, 1919, entitled Rotary water pump, and while the principles of these pumps are similar, 20 their construction, operation and results are essentially different, especially in that we now provide a water power pump motor by reason of simultaneous triple pumping operations.

25 The object of the invention is to provide a plurality of cut out rollers on each side of and in the path of movement of a plurality of rotary blades within a chamber the casing of which has a plurality of intakes and a

30 plurality of discharge openings arranged in pairs relative to the cut out rollers, whereby an inlet and an outlet is formed adjacent to each of said rollers, and affording triple pumping.

35 A further object of the invention is to provide a rotary mounting for a plurality of blades or vanes so arranged within the pump casing chamber as to have a pair of blades occupy the chamber spaces between 40 the cut out rollers, in certain conditions of a pumping operation, whereby induction is afforded between the rollers and the blade adjacent to one side of the rollers, and eduction is afforded between the same rollers and the blade adjacent the other or opposite side of the rollers, whereby triple pumping operations are produced.

A still further object of the invention is to provide a plurality of vanes or blades 50 mounted on a gear but which meshes with a pinion on the inner end of the cut out rollers for automatic revolution of the vanes and the rollers in pumping operations.

Various other objects, advantages and im- 55 proved results are attainable in the manu-

facture and application of the invention, as will be hereinafter fully set forth.

In the accompanying drawings forming part of this application:—

Figure 1 is a side elevation of a pump 60 embodying our invention.

Fig. 2 is an elevation with half of the casing removed.

Fig. 3 is a vertical sectional view.

Fig. 4 is a cross section.

Fig. 5 is a detail top view of a pair of 65 sub-casings and a pair of parts.

Fig. 6 is a detail elevation of one of the cut out rollers looking at the pinion end thereof.

The same reference characters denote the 70 same parts throughout the several views of the drawings.

In carrying out these improvements for a compound pump, we form or attach to the 75 outside of a cylindrical casing 1, a plurality of sub-casings 2. Preferably three of such sub-casings are arranged opposite each other on each side of the casing 1 at an angle thereto. The sub-casings open into a pump 80 chamber 3 formed by the casing 1, which has an intake or induction coupling 4 on one side of the longitudinal central plane of each pair of sub-casings, and an exhaust or eduction coupling 5 on the other side of such 85 plane, so that for every pair of sub-casings there is a pair of ports central of the periphery of the casing 1. The sub-casings are made conical for revolvably containing a conical cut-off roller 6, and a portion of the 90 head of the sub-casings extends over the periphery of the casing 1 to the flanges 7 of the casing, and said flanges are bolted together as at 8. The bottom of the sub-casings terminates adjacent to a hub 9 of the 95 casing 1, for a driven shaft 10. The casing 1 being fixed in stationary position as by suitable supports 11 bolted to a foundation 12, so that the shaft 10 may revolve in the casing hub 9.

The rollers 6 have a plurality of lengthwise grooves or cut-outs 13, the cut-outs of each roller being equal in number, as three 100 so that the cut-outs of adjacent rollers may be brought opposite each other in a pumping operation. The rollers 6 have spindles 14, journaled in the sub-casings, and the inner or small end of the rollers is provided with a pinion 15.

One of the important features of our in- 110

vention is the vane or blade hub 16 having gear teeth 17 on opposite faces thereof, with six vanes or blades 18 radiating from the periphery of the hub 16. These blades increase in width from the hub 16 to their outer end and appear as wedge or fan shape so as to fit the chamber 3 of like shape. The hub 16 is fixed or otherwise secured to the shaft 10 within the casing hub 9, and the roller pinions mesh with the teeth of the hub 16, for revolving the rollers in unison with the vanes or blades so that the blades will successively engage opposite cut outs of each pair of rollers as the latter are revolved during the revolution of the blades in a triple pumping operation.

It will be understood that the hub and pinion gearing is of such relative size or pitch as to automatically turn the rollers so as to place one cut out of each pair of adjacent rollers opposite and thereby form a passage for the vanes between the rollers.

It will be seen that the chamber 3 is divided into three sub-chambers by three pairs of rollers, and that each sub-chamber has an induction port 20 and an eduction port 21 controlled by the rollers arranged in co-operating pairs, thus affording a multiplicity of inductions and eductions to which may be coupled suitable fluid conveyer pipes leading in various directions to and from the pump, for furnishing motive power as desired.

Obviously the rollers and the vanes have such relative arrangement as to simultaneously open and close all the ports, during the revolution of the vanes for creating a suction in the sub-chambers which are separated by the pairs of rollers and these rollers separate adjacent eduction and induction ports, so that the vanes carry fluid from the induction port at one side of each pair of rollers and force the fluid through the eduction port at the other side of each pair of rollers, whereby continuous compound or triple pumping is produced during the revolution of the gear hub carrying the vanes.

We do not wish to be understood as confining ourselves to any particular size or capacity of the pump, to the number of cut off rollers and vanes, except as to their relative co-operation, nor to any particular means for driving the pump, nor to any particular material comprising the various

parts, neither do we wish to confine ourselves in the use or application of the pump, but reserve the right to make such changes and variations in the manufacture and practical application of the invention as may not be inconsistent with the appended claims. 60

Having thus described our invention what we claim as new and desire to secure by Letters Patent is:

1. In a compound rotary pump, a cylindrical casing, a hub gear revolvably mounted in the casing, a plurality of vanes radiating from the hub and fitting a chamber formed by said casing, a plurality of cut off rollers on each side of the casing and arranged in co-operating pairs for induction and eduction of fluid adjacent to each pair of rollers which have cut outs for the passage of the vanes therebetween, a pinion on the inner end of each roller and meshing with the hub gear, and means for revolving the hub. 75

2. In a compound rotary pump, a cylindrical casing, a revolvable vane hub having double gear faces, a plurality of vanes radiating from the hub between said faces, a plurality of cut off rollers arranged in co-operating pairs within the casing for the passage of the vanes between the rollers of each pair, a pinion on each of said rollers and meshing with the gear faces of said hub, and means for revolving the hub whereby an injection and an ejection is produced adjacent to each pair of said rollers. 85

3. In a compound rotary pump, a cylindrical casing forming a chamber, a vane hub revolvable in the chamber and having a gear on each side thereof, a plurality of vanes radiating from the periphery of the hub, a plurality of cut off rollers at each side of the chamber and arranged in co-operating pairs for the passage of the vanes 95 between the rollers of each pair, said rollers dividing the chamber into a plurality of sub-chambers, a pinion on each roller and meshing with the hub gear, and means for revolving the hub for unison movement of 100 the vanes and the rollers.

In witness whereof we hereunto set our hands in the presence of two witnesses.

MORIL V. ANDREWS.
STEPHEN W. HOLMAN.
